UNITED STATES PATENT OFFICE.

ADRIEN BOCHET, OF PARIS, FRANCE.

VIBRATION-EQUALIZING SUPPORT FOR MOTORS.

SPECIFICATION forming part of Letters Patent No. 715,954, dated December 16, 1902.

Application filed March 23, 1901. Serial No. 52,501. (No model.)

To all whom it may concern:

Be it known that I, ADRIEN BOCHET, of 14 Rue de Passy, Paris, France, engineer, have invented Improvements in Vibration-Equalizing Supports for Motors; and I do hereby declare the nature of my present invention and in what manner the same is to be performed to be clearly described and ascertained in and by the following specification.

10 My present invention relates to an improved vibration-equalizing support for motors, &c.

The object of this invention is to provide means for mounting the motors of motor-vehicles on the frames of such vehicles in such 15 a manner that the vibration of the motor will be taken up by the mounting and not be transmitted to the frame.

15 The invention is fully disclosed in the following specification, of which the accompanying drawings form a part, in which the separate parts of my improvement are designated by suitable reference characters in each of the views, and in which—

20 Figure 1 is a front view of a vehicle provided with my improvement, the motor being shown in dotted lines; and Fig. 2, a plan view with the motor removed, so as to show the mounting.

25 In the practice of my invention I connect with the axles A, only one of which is shown, a frame comprising side members B, and on said frame or the separate members thereof I place transverse supports S, which are preferably downwardly curved at the middle, as 30 shown at S², and on these supports S are placed the motor S³, which is shown in dotted lines in Fig. 1, and the crank-shaft S⁴ of which is provided with bearings S⁵, and as thus provided it will be seen that the motor is free to 35 swing laterally.

40 At each side of the motor are placed supports b, which are connected at their upper ends with the motor by means of ball-and-socket joints b², and the lower ends of the

supports b are loosely or pivotally connected 45 at b³ with springs R, secured at R² to levers C, mounted on and adapted to turn on pins O, secured to the axle A at O². One of the levers C is provided at its inner end with a link C², and the other is provided with a fork 50 F, having a pin i, which passes through the link C², and as thus supported it will be seen that the motion or vibration of the motor will be taken up entirely by the mounting or the supports thereof.

55 Having fully described my invention, what I claim as new, and desire to secure by Letters Patent, is—

1. A motor-vehicle having longitudinal frame members connected with the axles 60 thereof, transverse supports connected with said frame member, a motor mounted in said supports and adapted to swing laterally, said motor being provided with laterally-arranged supplemental supports loosely connected 65 therewith and with springs which are connected with the axle centrally thereof, substantially as shown and described.

2. A motor-vehicle, the frame of which is provided with transverse supports, a motor 70 mounted on said supports and adapted to swing laterally, supplemental supports connected with said motor laterally of its first-named connection, said supplemental supports being also connected with springs which 75 are secured to levers pivotally connected with the axle and adapted to swing vertically, one of said levers being provided with a link at its inner end and the other with a pin which passes therethrough, substantially as shown 80 and described.

In testimony that I claim the foregoing as my invention I have signed my name in presence of two subscribing witnesses.

ADRIEN BOCHET.
